PUNCH

Ralph E. Valentine, Buffalo, N. Y., assignor to
Curtiss-Wright Corporation, a corporation of
Delaware

Application January 19, 1944, Serial No. 519,065

10 Claims. (Cl. 164—119)

This invention relates to a tool characterized by features which adapt it particularly, although not necessarily, for punching a part to mark thereon the locations of, or to form directly therein, holes which will be aligned with pre-formed concealed holes in a mating part.

In the manufacture of aircraft, it is frequently impracticable to pre-drill certain parts which are to be fastened to mating parts. For example, in the installation of cowlings, fillets, de-icing "boots" and the like, it is feasible, owing to the slight variations in the contours of the mating parts, to pre-drill only one of such parts, the other being drilled after the two parts have been fitted. In this way proper alignment of the holes which are to accommodate the fastenings is insured. To locate the centers of the holes in a part to be drilled, it has heretofore been the practice to scribe circles about the pre-drilled holes. The undrilled mating part is then fitted and temporarily secured in place over the pre-drilled part and while so fitted and secured, intersecting arcs of the same radius as the circles on the pre-drilled part and having their centers located in spaced relation around the circumferences of said circles, are scribed on the part to be drilled. The arc intersections thus provided indicate on the undrilled part the locations at which holes drilled, punched, or otherwise formed in such part will be in alignment with the holes in the pre-drilled part. The undrilled part is then removed and after being drilled or punched at the points indicated is permanently secured in place.

One object of the present invention is to provide a tool which may be availed of to mark the locations of, or to form directly, holes in one part which are accurately aligned with pre-formed holes in a mating part, thereby avoiding the necessity of scribing the parts in the manner described, and hence eliminating the operations involved and the possibility of error attendant with such operations.

A further object is to provide a tool which will act uniformly regardless of the manner in which it is operated.

A still further object is a novel design and arrangement of the parts of the tool, whereby to obtain simplicity in construction and ease of operation.

The invention is illustrated in the accompanying drawing in which:

Figure 1 is a side elevational view of a tool embodying the features of the invention.

Figure 2 is a longitudinal section through the tool.

Figure 3 is an end view of the tool.

Figure 4 is a detail section taken along line 5 4—4 of Figure 1.

Figure 5 is a sectional view of a modified form of tool.

The tool, as illustrated, includes a tubular body 9, one end of which is closed by a threaded plug 10. The opposite end of the tubular body 9 is suitably secured in a socket 11 formed in a head-piece 12, the bottom wall of the said socket being formed with an opening 13. An anvil 14, which is carried by the head-piece 12, is formed with a tongue portion 15, the latter being spaced from the lower face of the head-piece and carrying a pilot pin 16. A punch element 17 occupies the tubular body 9, the said element being formed or provided with a plunger-like body 18, a head 19 and a shank 20, the tip of the shank, in the embodiment illustrated in Figures 1 and 2, being pointed and the axis of the shank being in alignment with the axis of the pilot pin 16. A main spring 21 is located between the plug 10 and the head 19 of the punch element while a secondary spring 22 is located between the lower end of the body of the punch element and the end wall of the socket 11. The two springs normally support the punch element in the location illustrated in Figure 2 of the drawing, in which location the tip of the shank 20 is retracted with respect to the outer face of the head-piece and is located within and substantially centrally of the opening 13. An actuating lever, indicated at 23, is forked at 35 one end, the branches of the forked end straddling the head-piece 12 and being pivotally connected thereto by a pin 24. The opposite or free end of the actuating lever provides a handle. A spring 25 which is connected at one end to the head-piece 12 is connected at its opposite end to an arm 26. One end of the latter is pivotally connected to a pin 27 carried by the actuating lever while the opposite end which is notched extends through a longitudinally extending slot 28 45 formed in the wall of the tubular body 9 and engages the under side of the head 19 of the punch element. The spring 25 acting through the agency of the arm 26 normally holds the actuating lever in the extended, or full-line, position illustrated, in which position the branches of the forked end of the lever engage shoulders 29 on the head-piece 12.

In the use of the tool the tongue portion of the anvil is inserted under the edge of an un-drilled sheet 30, as best shown in Figure 2, to

cause the pilot pin 16 to enter a pre-drilled hole 31 in a mating sheet 32. The lever 23 is then actuated by moving the handle thereof toward the tubular body 9, the limit of such movement being reached when the end of the handle engages the said body, as indicated in dotted lines in Figure 1. When the lever 23 is actuated in the manner described the resultant movement of the arm 26 is transmitted to the punch element and the latter is moved axially toward the plug 10, compressing and hence loading the spring 21 as it moves in such direction. As the handle portion of the lever 23 approaches the tubular body 9, the nose portion 33 of the arm 26 engages an inclined end wall 34 of the slot 28. The free end of the said arm is thereby caused to swing outwardly and the head 19 of the punch element is released. The spring 21 is thereupon operative to propel the punch element rapidly in the direction of the part to be marked. Although the secondary spring 21 tends slightly to decelerate the punch element after the latter reaches its normal position, its inertia is great enough to carry it well beyond its normal position. The shank 20 of the punch element, therefore, is projected through the opening 13 against the action of the spring 22 and the pointed end thereof is caused to strike sharply and form an indentation in the surface of the sheet 30. The travel of the punch element being arrested by its engagement with the sheet 30, the spring 22 restores the punch element to its normal position. The lever 23 is then released to permit the spring 25 to return to its original position, the arm 26 riding first over the convolutions of the spring 21 and then over and under the head of the punch element so that when the lever is again actuated the punch element will be caused to function in the manner described.

It will be apparent from the foregoing that when the tool is employed in the manner described the sheet 30 will be marked to indicate the location of the center of a hole which will be in exact alignment with the pre-drilled or punched hole in which the pilot pin 16 is located. As the spring 21 is always loaded to the same degree when the lever 23 is actuated, the indentations which are formed in the sheet 30 will all be of substantially the same size, depth and appearance. The action of the tool, therefore, will be uniform regardless of the care or speed with which it is actuated.

Instead of marking the sheet 30 to indicate the locations of the holes, the latter may, if desired, be formed directly by the tool, as illustrated in Figure 5. In such case the pilot pin 16 is carried by a die element 35. The latter is accommodated in a suitable recess formed in the tongue portion of the anvil 14 in such a manner that the pilot pin may be utilized as described in connection with the embodiment shown in Figure 1. The end of the shank 20 in this embodiment is formed with a cutting edge which cooperates with a cutting edge on the die element 35. An opening 36 in the die element, which the shank portion of the punch element enters in the punching operation, accommodates a pad 37 of rubber or other resilient material for ejecting from the opening the slugs formed in the use of the tool. The holes punched in the sheet 30 by the tool will, for the reasons heretofore noted, be in alignment with the holes in the sheet 32.

Apart from the use of the tool in the manner and for the purpose described, the tool may also be availed of to punch a part at a predetermined

distance from a marginal edge of the part. In such case the inner wall of the body portion of the anvil is engageable with the marginal edge of the part to gauge the distance from such edge 5 at which the punch element is to mark or perforate the part, there being no occasion, of course, when using the tool in this manner to utilize the pilot pin.

I claim as my invention:

10. 1. A tool for use in connection with the forming of a hole in one part which is aligned with a pre-formed hole in a mating part, said tool including a body, means carried by said body which may be positioned under said first mentioned part, a pilot pin carried by said means which is adapted to be inserted in said pre-formed hole to locate said body in the proper relation with respect to said first mentioned part, a punch element carried by said body for acting on said first mentioned part, resilient means, means for loading said resilient means, and means for utilizing the energy thereby stored in said resilient means to actuate said punch element.
15. 2. A tool for use in connection with the forming of a hole in one part which is aligned with a pre-formed hole in a mating part, said tool including a body, means carried by said body which may be positioned under said first mentioned part, a pilot pin carried by said means to locate said body in the proper relation with respect to said first mentioned part, a punch element carried by said body in alignment with said pilot pin for acting on said first mentioned part, resilient means, means for loading said resilient means, and means for utilizing the energy thereby stored in said resilient means to actuate said punch element.
20. 3. A tool for use in connection with the forming of a hole in one part which is aligned with a pre-formed hole in a mating part, said tool including a body, means carried by said body which may be positioned under said first mentioned part, a pilot pin carried by said means which is adapted to be inserted in said pre-formed hole to locate said body in the proper relation with respect to said first mentioned part, a punch element carried by said body for acting upon said first mentioned part, resilient means, and means for retracting said punch element to compress and thereby load said resilient means, said punch element being thereafter releasable to permit said resilient means to actuate it.
25. 4. A tool for use in connection with the forming of a hole in one part which is aligned with a pre-formed hole in a mating part, said tool including a body, means carried by said body which may be positioned under said first mentioned part, a pilot pin carried by said means which is adapted to be inserted in said pre-formed hole to locate said body in the proper relation with respect to said first mentioned part, a punch element carried by said body for acting upon said first mentioned part, resilient means, and means for retracting said punch element to compress and thereby load said resilient means, said last named means releasing said punch element when it has been retracted to a predetermined position, whereby to permit said resilient means to actuate it.
30. 5. A tool for use in connection with the forming of a hole in one part which is aligned with a pre-formed hole in a mating part, said tool including a body, means carried by said body which

may be positioned under said first mentioned part, a pilot pin carried by said means which is adapted to be inserted in said pre-formed hole to locate said body in the proper relation with respect to said first mentioned part, a punch element carried by said body for acting upon said first mentioned part, resilient means, means for retracting said punch element to load said resilient means, and means for automatically releasing said punch element when said resilient means has been loaded to a predetermined degree, whereby to permit said resilient means to actuate said punch element.

6. A tool for use in connection with the forming of a hole in one part which is aligned with a pre-formed hole in a mating part, said tool including a body, means carried by said body which may be positioned under said first mentioned part, a pilot pin carried by said means which is adapted to be inserted in said pre-formed hole to locate said body in the proper relation with respect to said first mentioned part, a punch element carried by said body for acting upon said first mentioned part, resilient means, means for retracting said punch element to load said resilient means, and means for automatically releasing said punch element when it has been retracted to a predetermined limit, whereby to permit said resilient means to actuate it.

7. A tool for use in connection with the forming of a hole in one part which is aligned with a pre-formed hole in a mating part, said tool including a tubular body, means carried by said body which may be positioned under said first mentioned part, a pilot pin carried by said means which is adapted to be inserted in said pre-formed hole to locate said body in the proper relation with respect to said first mentioned part, a punch element in said body, said punch element having a plunger-like body and a shank portion for acting on said first mentioned part, resilient means, means for retracting said punch element to load said resilient means, and means for automatically releasing said punch element when it has been retracted to a predetermined limit, whereby to permit said resilient means to actuate it.

8. A tool for use in connection with the forming of a hole in one part which is aligned with a pre-formed hole in a mating part, said tool including a tubular body, means carried by said body which may be positioned under said first mentioned part, a pilot pin carried by said means which is adapted to be inserted in said pre-formed hole to locate said body in the proper relation with respect to said first mentioned part, a punch element in said body, resilient means acting upon said punch element in opposite directions to hold the latter in a predetermined position in said body, means for retracting said punch element to load one of said resilient means, and means for releasing said punch

element when it has been retracted to a predetermined limit, whereby to permit said last mentioned resilient means to actuate it, said last mentioned resilient means being operative in so doing to advance said punch element beyond said predetermined position.

9. A tool for use in connection with the forming of a hole in one part which is aligned with a pre-formed hole in a mating part, said tool including a tubular body, means carried by said body which may be positioned under said first mentioned part, a pilot pin carried by said means which is adapted to be inserted in said pre-formed hole to locate said body in the proper relation with respect to said first mentioned part, a punch element in said body, said punch element having a plunger-like body and a shank portion for acting upon said first mentioned part, resilient means acting upon the body of said punch element in opposite directions to hold the latter in a predetermined position, means for retracting said punch element to compress and thereby load one of said resilient means, and means for automatically releasing said punch element when it has been retracted to a predetermined limit, whereby to permit said last mentioned resilient means to actuate it, said last mentioned resilient means being operative in so doing to advance said punch element beyond said predetermined position.

10. A tool for use in connection with the forming of a hole in one part which is aligned with a pre-formed hole in a mating part, said tool including a tubular body, means carried by said body which may be positioned under said first mentioned part, a pilot pin carried by said means which is adapted to be inserted in said pre-formed hole to locate said body in the proper relation with respect to said first mentioned part, a punch element in said body, said punch element having a plunger-like body and a shank portion for acting upon said first mentioned part, resilient means acting upon the body of said punch element in opposite directions to hold the latter in a predetermined position, a lever pivotally connected to said first mentioned body, an arm pivotally connected to said lever and engageable with said punch element, said lever being movable toward said first mentioned body to cause said arm to retract said punch element and thereby load one of said resilient means, means for automatically effecting the release of said punch element when it has been retracted to a predetermined limit, whereby to permit said last mentioned resilient means to actuate said punch element, said last mentioned resilient means being operative in so doing to advance said punch element beyond said predetermined position, and means for restoring said lever to its original position when it is released.

RALPH E. VALENTINE.
